UNITED STATES PATENT OFFICE.

ALBERT H. DE VOE, OF WESTFIELD, NEW JERSEY, ASSIGNEE TO THE SINGER MANUFACTURING COMPANY, A CORPORATION OF NEW JERSEY.

SEAM FOR SEWED ARTICLES.

1,279,846.

Specification of Letters Patent. Patented Sept. 24, 1918.

Application filed December 27, 1916. Serial No. 139,074.

To all whom it may concern:

Be it known that I, ALBERT H. DE VOE, a citizen of the United States, residing at Westfield, in the county of Union and State of New Jersey, have invented certain new and useful Improvements in Seams for Sewed Articles, of which the following is a specification, reference being had therein to the accompanying drawings.

10 This invention relates to seams for sewed articles and has for an object to provide a seam wherein upper and lower plies of fabric are secured together, or to the top and bottom faces of intermediate fabric material, by one or more series of connected penetrative thread-loop structures, in such a manner that the connecting thread-portions are hidden from view.

20 More particularly, the invention has for an object to provide a seam wherein the plies of a longitudinally folded strip of tape, braid or the like, are connected by a series of blind stitches spaced from the line of fold.

25 A further object of the invention is to provide a seam wherein a strip of binding material is blind-stitched to the marginal portion of a body-fabric.

30 Further objects of the invention will appear from the following description and claims.

These objects are attained by the improved seam structure which, in its preferred embodiment, comprises a body-fabric presenting an edge which is covered by a longitudinally folded strip of tape. A line of blind stitches, spaced from the folded edge of the binding strip, connects the upper and lower plies of the latter and passes through the body-fabric. The line of blind-stitches comprises a series of keyed, penetrative, thread-loop structures each of which enters and emerges from the inner or hidden surfaces of the upper and lower plies of the folded binding strip, preferably without showing at the outer or visible surfaces of said plies. A convenient mechanism for carrying the invention into effect is disclosed in my copending application Serial No. 50 139,073, filed December 27, 1916.

In the accompanying drawings, Figure 1 is a perspective view illustrating a convenient mechanism for carrying the invention into effect and Fig. 2 is a perspective view of 55 the seam; a portion of the body-fabric being

shown in dotted lines to reveal the connecting stitches.

In the preferred embodiment of the invention, as illustrated, the seam comprises a body-fabric 1 presenting an edge 2 about 60 which is folded the binding strip 3 having upper and lower plies 4 and 5, respectively, which plies may be considered as integrally connected by the fold 6. The plies 4 and 5 are further connected by a line 7 of blind- 65 stitches formed within the marginal portions 8 and 9, respectively, of said plies and spaced from the fold 6.

The line of blind-stitches comprises a series of keyed, penetrative, thread-loop structures 8 each of which enters the inner or hidden surface of the upper ply 4 at the point 10, emerges from said surface at 11, passes downwardly through the intermediate fabric material 1 to the lower ply 5, enters the inner or hidden surface of the ply 5 at 12 and emerges from said surface at 13. In the present instance the penetrative thread-loop structures 8 of the series are connected together by the thread-portions 14, 14 which 70 extend along the inner or hidden surfaces of the plies 4 and 5 of the folded binding material 3. While a seam wherein the portions of the thread-loop structures between the points 10 and 11, or 12 and 13, do not show 75 at the outer or visible surfaces of the plies 4 and 5 is preferred, it is to be understood that such portions need not necessarily be "blind" but may extend entirely through the thickness of the plies 4 and 5 within the scope of 80 the invention. In the present instance a two-thread lock-stitch example of keyed thread-loop structure is shown, the keying being accomplished by the interlocking of the upper and lower threads at the point 15. The invention is not limited, however, to the use of 85 a lock-stitch or any other type of stitch. Furthermore, in the embodiment illustrated, the location of the locking point 15 is immaterial.

100 Although the seam may be produced by hand, a convenient mechanism for carrying it into effect may comprise a binder 16 of the well known "English" type having the end-portions of its inclined, U-shaped, fold-inverting edge, disposed close to and in rear of the path of the reciprocating needle 17, whereby the needle at each descent will split the material of the U-shaped fold 18 at the points 19 and 20. If the edge portion of a 105 110

body-fabric 1 is presented to the binder, it will be covered by the strip 3 in such a manner that the fastening stitches will not be visible at either side of the seam. If the body-fabric is not presented to the binder the stitch-forming mechanism will act upon the binding strip 3 alone and stitch the upper and lower plies thereof together to form a tubular structure such as shown at the right of Fig. 2. The direction of feed of the material is indicated by an arrow.

Having thus set forth the nature of the invention, what I claim herein is:—

1. In a seam for sewed articles, in combination, upper and lower plies of material, having superimposed edge-portions and a line of fastening stitches connecting said edge-portions, said stitches including a series of keyed, penetrative, thread-loop structures each entering and emerging from the inner or hidden surfaces of said plies without showing at the outer or visible surfaces of said plies.
2. In a seam for sewed articles, in combination, upper and lower plies of material, having superimposed edge-portions, and a line of fastening stitches connecting said

edge-portions, said stitches including a series of keyed, penetrative, thread-loop structures each entering and emerging from the inner or hidden surfaces of said plies.

3. In a seam for sewed articles, in combination, a longitudinally folded strip of material presenting upper and lower plies, and fastening stitches connecting said plies at a distance from the line of fold, said stitches including a series of keyed, penetrative thread-loop structures each entering and emerging from the inner or hidden surfaces of said plies.

4. In a seam for sewed articles, in combination, a body-fabric presenting an edge, a longitudinally folded strip of binding material covering said edge and having upper and lower plies disposed mainly at opposite sides of said body-fabric, and fastening stitches including a series of keyed, penetrative, thread-loop structures each entering and emerging from the inner or hidden surfaces of said plies and passing through the body-fabric.

In testimony whereof, I have signed my name to this specification.

ALBERT H. DE VOE.
